UNITED STATES PATENT OFFICE.

NILS H. ANDERSON, OF HARTFORD, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

PLATEN-SHIFTING MECHANISM FOR TYPE-WRITING MACHINES.

1,155,635.

Specification of Letters Patent.

Patented Oct. 5, 1915.

Application filed April 27, 1908. Serial No. 429,408.

To all whom it may concern:

Be it known that I, NILS H. ANDERSON, a citizen of the United States, residing at Hartford, in the county of Hartford and 5 State of Connecticut, have invented certain new and useful Improvements in Platen-Shifting Mechanism for Type-Writing Machines, of which the following is a full, clear, and exact description, such as will enable 10 others skilled in the art to which it appertains to make and use the same.

This invention relates to that class of typewriting machines wherein the type carriers are provided with two or more types 15 and wherein the platen is normally held in position to receive imprints from one of the sets of type, the type carrier and the platen being relatively shiftable to enable the platen to receive imprints from the other set 20 or sets of type.

One of the objects of the invention is to provide mechanism for moving the shiftable part, which will be of simple construction and which may be operated without producing noise. 25

Another object of the invention is to provide noiseless shifting mechanism for the platen carriages of typewriting machines which will be positive, reliable and accurate 30 in operation.

Another object is to provide shifting mechanism for the platen carriages of typewriting machines of that type wherein the platen is normally held in a position to receive imprints from the middle set upon a type bar employing three sets of types of such construction that the position of the platen, whether in normal or in shifted position, will be accurately determined. 35

A further object thereof is to provide an improved noiseless stop for the shift levers or other moving parts of a typewriter. 40

Other objects will be in part obvious and in part pointed out hereinafter.

The invention accordingly consists in the features of construction, combinations of elements and arrangement of parts which will be exemplified in the construction hereinafter described, and the scope of the application of which will be indicated in the appended claims. 45

In the accompanying drawings wherein is illustrated one of the various possible em-

bodiments of my invention, Figure 1 is a plan view of a preferred form of shifting mechanism, portions of the machine being broken away better to illustrate the same. Fig. 2 is a view in section taken on line 2—2, Fig. 1. Fig. 3 shows a modified form of counterbalancing mechanism for the shiftable carriage. Fig. 4 is an enlarged view showing the positions of the cams in the cap shifted position. Fig. 5 is a view in elevation, drawn on an enlarged scale, of the shift cams, showing the position assumed by these parts when the platen carriage is in normal position. Fig. 6 shows the positions of these parts in the figure shifted position. Fig. 7 is a diagrammatic view, showing the shape and the position of the cam path provided in one of the cam members when such member is in normal position, as shown in Fig. 2, or in its shifted position, as shown in Fig. 4 and showing also the "dwell" at the ends of the cams. Fig. 8 is a view in section of a locking roll and the adjusting parts therefor. Fig. 9 is a view in elevation of a slightly modified form of the shifting mechanism, the parts being shown in normal position. Fig. 10 is a similar view but showing the parts in the cap shifted position. Fig. 11 is a rear elevation, partly in section, taken on the line 11—11, Fig. 9, looking in the direction of the arrows. Fig. 12 is an elevational view, showing the shifting mechanism with the parts in the positions they assume when the figure shift key is depressed, showing also the connections of the shift mechanism with the vertically shiftable carriage and the guiding means for the same. Fig. 13 is a top plan view of the shiftable rail upon which the platen carriage travels, and showing the means for compelling an equal movement of both ends of said carriage when the same is shifted. Fig. 14 is a view in elevation, showing the mechanism illustrated in Fig. 13 in its central position. Fig. 15 is a similar view of this structure, showing the position of the parts when the platen carriage is shifted to its upper or cap position. Fig. 16 is a diagrammatic view, showing the disposition of the parts when the platen carriage is in its normal central position, as shown in Fig. 14. Figs. 17 and 18 show the positions assumed by these parts when the platen carriage is 55 60 65 70 75 80 85 90 95 100 105

shifted to the positions shown in Figs. 15 and 12, respectively. Fig. 19 is a view in perspective of a novel form of stop employed silently to arrest the movements of 5 certain of the parts employed herein.

Similar reference characters refer to similar parts throughout the several views of the drawings.

Referring now to the drawings, 1 indicates a portion of the frame of a typewriting machine and 2 represents a table or bed adapted to support a set of printing members which, in the present instance, are constituted by straight thrust type bars, one of 10 which is shown at 3. The type bars are provided with a plurality of printing characters or types, in the present instance three in number, and are adapted to be projected forwardly upon the supporting bed against 15 the platen 4 by means of actuating mechanism not herein shown. The platen, in the present instance, is a thin metallic plate or strip which extends longitudinally of the platen carriage in front of a paper roll 5, 20 of usual construction. The platen and platen roll are mounted in a vertically shiftable carriage 6, which rides, during letter spacing, upon a shiftable rail 7, balls 8 being interposed between the rail and said 25 carriage. The rear portion of the platen carriage has a vertical and longitudinal sliding contact with an abutment 10, which is formed, in the present instance, by an up-standing portion of a tie rod 11 which extends 30 transversely of the machine.

Rail 7, which is normally held in such position as will enable the platen to receive imprints from the middle set of types of the type bars, is caused to travel in a vertical plane during the shifting operation and in parallel relation with the faces of 40 the types, by means of arms 13 and 14, pivoted at 15 and 16 to said rail, the opposite ends of said arms being connected respectively with oscillating arms 17 and 18, fastened to a balancing shaft 20, which is suitably journaled in a fixed portion of the machine. Balancing arms 13 and 14, intermediate their ends slide in trunnions 21 and 22, respectively, which are journaled 45 in the center tie.

When rail 7 is shifted either up or down from its normal intermediate position, arms 17 and 18 are rocked in an opposite direction 55 from that in which the carriage is shifted, the outer ends thereof swinging in an arc of a circle, the radius of which is in such proportion to the radius of the arc in which the arms 13 and 14 swing that the rail will 60 travel in a vertical line, the latter arms sliding in the trunnions during the shifting operation.

The mechanism above described is not claimed specifically herein but is illustrated 65 in order to impart a clear understanding of

the construction and operation of the shifting mechanism which I shall now proceed to describe.

Suitably journaled at either end in the frame of the machine is an oscillating shift 70 shaft 23 which is provided, in the present instance, with a pair of rearwardly extending arms 24 and 25, which are mounted at opposite ends of the shift shaft, the outer ends of said arms being connected with the 75 vertically shiftable rail 7 by means of links 26 and 27 respectively. The shift shaft is provided with an off-set portion or yoke 28 upon which is mounted a pair of cam members 30 and 31. The cam members, in this 80 embodiment of the invention, are permanently fixed upon the yoke, although, if desired, they may be adjustably mounted thereon, as shown in the embodiment and illustrated in Figs. 9 to 11, inclusive, wherein 85 they are adjustable radially upon the yoke around the central axis of the shift shaft. Each of the cam members, in the present instance, is provided with a cam slot, said slots being shown at 32 and 33, and these slots 90 have dwells at both ends thereof, the object of which will be set forth hereinafter. The dwells of the cam members located nearest the yoke lie in coincidence with the axis of oscillation 34 of the shift shaft. The cam members 30 and 31 are also provided with 95 exterior cam surfaces, as at 35 and 36.

Cam members 30 and 31 are oscillated in opposite directions by means of a pair of pivotally mounted secondary levers 37 and 38, respectively, one of these levers being provided for each cam member. These levers are mounted upon pivots 39 provided in radially adjustable brackets 45', which are seated in a fixed bracket 45" secured to the frame of the machine. The adjustment of the movable brackets is in an arc struck from a radius having the central axis 34 of the shift shaft as a center. Levers 37 and 40 38 are provided with cam rolls 40 and 41 respectively, one of which is received in a cam slot of each of cam members 30 and 31. These rolls, when the cam members are in normal position, engage the dwells thereof which are located in coincidence with the central axis 34 of the shift shaft. The object of this construction is to enable either one of these levers to be swung to project its roller along a cam groove, thereby swinging the cam members to oscillate the shift shaft, while the other of said levers may remain inactive. Levers 37 and 38 are also provided with rolls 42 and 43, each of which engages the exterior cam portions 35 and 36, respectively, of the cam members, said 45 rollers co-operating to hold said cam members in their normal position, as shown in Fig. 2 of the drawings. These latter rolls may be adjusted toward or from the cam surfaces 35 and 36, of the cam members by 50 100 105 110 115 120 125 130

means of eccentrically mounted studs 44, as shown in Figs. 5 and 8 of the drawings.

The shift levers are shown at 45 and 46, pivoted at 47 and 48 respectively, to a fixed portion of the frame of the machine, and are held in an upper position by means of springs 50 and 51, respectively. The rear ends of shift levers 45 and 46, are forked as at 52 to receive rolls 53 and 54, provided upon the forward ends, respectively, of the secondary levers 37 and 38. These secondary levers, as will be noted from an inspection of Fig. 1 of the drawings, are each constituted by a pair of side pieces of corresponding shape, which are held in fixed relation by the pivot upon which they swing and by the pivots of the several rolls carried thereby.

Silent stops 55 and 56, are provided for arresting the movements of each of the shift levers, both in their upward and downward strokes, and since these stops are similarly constructed, but one thereof need be described. One of these stops, which is shown in perspective in Fig. 19 and in elevation in Fig. 2 of the drawings, is composed of a thin, flat piece or strip of spring metal, which is bent backward at its opposite edges and caused to assume a contour, in edge view, similar to substantially that of a letter C. The bentback edges of this strip are secured to a bracket 57, which is fastened to the frame of the machine, and the side thereof which is presented to the shift levers is preferably covered with a thin facing of felt or other elastic substance 58. The shift levers 45 and 46, in their position of rest, abut against the lowermost of these stops, as shown in Fig. 2, and when the rear end of either shift lever is swung upwardly, due to the depression of the forward end thereof, it abuts against the other stop, as shown in Fig. 12 of the drawings. The resilience of a stop constructed in this manner is but slight, and yet it is sufficient to cushion the ends of the strokes of the shift levers, and thus forms a very effective cushioned stop which will reduce noise to a minimum.

The platen carriage may be balanced or held in equilibrium in its normal central position by means of a spring 60, which is extended between a fixed portion of the frame and an extension of one of the arms 24 or 25, which extend rearwardly from the shift shaft and, if desired, a balancing spring, such as shown at 61, in Fig. 3, may be attached to the frame of the machine, as at 62, and also attached to a collar 63 which is radially adjustable upon the shift shaft, the adjustment of this collar operating to change the tension of the spring.

Having thus described the construction of this embodiment of the invention, the operation thereof may now be understood.

Assuming the platen carriage to be held

in its normal central position with cam rolls 40 and 41 occupying the dwells of the cam paths which are located in coincidence with the central axis 34 of the shift shaft, and in which position rolls 42 and 43 of levers 37, 70 and 38, respectively, engage the exterior cam portions 35 and 36 of the cam members and lock them accurately in said central position, a depression of either of the shift levers will, through either of the secondary levers 37 or 38, cause one of the cam rolls to traverse its cam path whereby the cam members will be oscillated to shift the platen through an oscillation of the shift shaft, the direction of the shifting movement, of course, depending upon the particular shift lever depressed. When the cam roll reaches the dwell formed in the cam slot near the end of the cam, the platen will be in the proper position to receive the imprints of the upper or lower sets of types upon the type bar and a slight movement in either direction by the cam roll will not operate to change the position of the platen. During this shifting operation, the locking rolls 90 which engage the exterior portions of cam members move out of the path thereof, as clearly shown in Figs. 5 and 6, respectively, wherein the positions of the rolls relative to the oscillatory cam members are shown when the carriage is in both of its shifted positions. At this point it may be noted that by the term "dwell" as used herein is meant that portion of the cam members which is struck from an arc having the radius of 100 either of the secondary levers for a center. The extents of these dwells are such that slight movements of the cam rolls when engaged therewith will not effect a movement of the cam.

In the diagram of Fig. 7, the central line of one of the secondary levers is shown, together with the positions assumed by the various cam rolls when the platen carriage is in normal, and in one of its shifted positions. The solid line represents the pathway of one of the cam members, for instance, such as is shown in Fig. 4 of the drawings, wherein it is shown lying in normal position, and the dotted line represents said cam member in its shifted position, as shown in Fig. 5. The points 64 and 65 represent the dwell of the cam at the central axis of the shift shaft and the points 66 and 67 represent the dwell occupied by the cam roll when the carriage reaches its shifted position. The movements of the levers 45 and 46 are arrested in their downward positions by means of the stop 56 and in their upward positions by stop 55, and springs 51 and 52, which urge the shift levers to their normal positions, also operate to move the secondary levers 37 and 38 to their normal positions, wherein the rolls 40 and 41 thereof engage respectively, the portions of the cam mem-

bers which lie in coincidence with the axis of oscillation of the shift shaft. The spring 60 which operates as a balancing device to hold the parts in equilibrium also assists in the returning of the platen carriage to its normal central position when the same has been depressed.

In the embodiment of the invention shown in Figs. 9, 10 and 11, the shift levers 45 and 46 are connected directly by means of cam rollers to the shift cams 30 and 31 respectively, which are mounted upon the yoke 28 of the shift shaft. The cam members 30 and 31, are also adjustably mounted upon the yoke, the adjustment thereof being effected by means of adjusting screws 68, the clamp screws 70 and 71 operate to hold the adjustable parts in their adjusted position. The cam members 30 and 31, as in the embodiment first above described, are provided with grooves having cam dwells, corresponding dwells thereof occupying positions coincident with the axis of oscillation of the shift shaft, the other dwells being located at the ends of the cam slots. The cam members are also provided with the exterior dwells with which locking rolls 72 and 73 upon the shift levers engage to hold the parts located when the carriage is in normal central position.

When one shift lever is operated, as 46, lifting the roller 41, said roller traverses the groove of cam 31, rocks the yoke 28, shift shaft 23 and arms 24 and 25, thus lifting the carriage to its upper position. Meanwhile the lock roll 72 follows the cam surface 36 during the first part of the shift movement or until the cam is under control of roll 41. Similarly, on the return stroke, the roll 72 engages the cam surface 36 before the roll reaches the central position, and again locks the cam in normal position. During the operation of either shift mechanism, the roll 40 or 41 of the other mechanism remains in alinement with the axis 34 of the shift shaft.

In both of the embodiments of my invention above described, the platen carriage is guided during its shifting movements by means of the arms 13 and 14 which are attached to the opposite ends of the shift rail and which operate to guide the platen carriage as above described. The platen carriage is, therefore, caused to travel in a substantially vertical line during the shifting operation and is maintained in a plane parallel to that occupied by the faces of the type. The particular construction of this mechanism, however, forms no part of the invention embodied in the present specification.

It will accordingly be seen that I have provided platen shifting mechanism for typewriting machines which will operate in an extremely simple, yet efficient, manner.

65. The platen carriage, while normally locked

in its normal central position may be readily shifted either upwardly or downwardly and the shift positions thereof, as well as the normal position are accurately determined. Moreover, a slight movement of either of the shift levers when the platen carriage is in its normal or shifted positions will not operate to move the same.

A further and very important advantage accruing by reason of the present structure resides in the fact that the entire shifting operation may be effected without producing noise.

While I have shown my invention as adapted for typewriting machines of the above type, it will be understood that the same may be readily adapted to machines of other types.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

Having described my invention what I claim as new and desire to secure by Letters Patent, is:

1. In a typewriting machine, the combination with a support for a set of types and a platen, one of which is shiftable to change the disposition of the type with respect to the platen, of a pair of rotatably mounted cam members adapted when actuated to move the shiftable part in opposite directions from a normal central position, and an independent actuator for each of said cam members movable relatively thereto, said actuators coöperating to hold said shiftable part in normal central position.

2. In a typewriting machine, the combination with a support for a set of types and a platen, one of which is shiftable to change the disposition of the type with respect to the platen, of a pair of rotatably mounted cam members adapted when actuated to move the shiftable part in opposite directions from a normal central position, and key operated means connected at one end to said cam-members for actuating each of said cam members and for holding them in a position of rest, whereby the shiftable part will be held in its normal central position.

3. In a typewriting machine, the combination with a support for a set of types and a platen, one of which is shiftable to change

- the disposition of the type with respect to the platen, of a pair of oscillatory cam members having cam paths adapted when actuated to move the shiftable part in opposite directions from a normal central position, and a key operated actuator for each of said members having means for traversing the cam path thereof to thereby actuate the cam member, each of said key operated actuators having means which engages one of said oscillatory members and cooperates with the corresponding means upon the other thereof to hold the shiftable part in its normal central position.

4. In a typewriting machine, the combination with a support for a set of types and a platen, one of which is shiftable to change the disposition of the type with respect to the platen, of a pair of oscillatory members having cam paths connected with said shiftable part, and an actuating device for each of said members having means for traversing the cam paths thereof, whereby said members may be oscillated to shift the shiftable part, and means carried by said actuating devices for engaging said oscillatory members and for holding the same in such position as will hold the shiftable part in a normal central position.

5. In a typewriting machine, the combination with a support for a set of types and a platen, one of which is shiftable to change the disposition of the type with respect to the platen, of a pair of oscillatory members having cam paths connected with the platen, each of said members being adapted to move the shiftable part from a normal central position in a direction opposite to that in which it is moved by the other thereof, a key operated actuating device for each of said oscillatory members provided with a part which traverses the cam path thereof, thereby to actuate the same, each of said actuating devices being also provided with a part which limits the oscillatory movement of one of said cam members in one direction.

6. In a typewriting machine, the combination with a support for a set of types and a platen, one of which is shiftable to change the disposition of the type with respect to the platen, of a pair of oscillatory cam members connected with the shiftable part, each of which is adapted to shift the same from a normal central position in a direction opposite to that in which it is shifted by the other thereof, and an independent operating actuating device for each of said oscillatory members adapted to actuate the same and also adapted to hold the same in such position as will lock the shiftable part in its normal central position.

7. In a typewriting machine, the combination with a support for a set of types and a platen, one of which is shiftable to change the disposition of the types with respect to the platen, of a pair of oscillatory members connected with the platen, each of which is provided with a cam path, an independent actuating device for each of said oscillatory members provided with means which traverses the cam path thereof, and means upon said actuating devices which coöperate with said oscillatory members to hold the shiftable part in a normal position.

8. In a typewriting machine, the combination with a support for a set of types and a platen, one of which is shiftable to change the disposition of the type with respect to the platen, of a pair of oscillatory members connected with said shiftable part and provided with cam paths, said oscillatory members being adapted to be independently actuated in opposite directions to shift the shiftable part in opposite directions from a normal intermediate position, a pair of key actuated members each of which is provided with a roll which traverses the cam path of one of said members, whereby said members may be actuated, and rolls carried by said key operated members adapted to engage said oscillatory members and lock the same in such position as will cause the shiftable part to be held in a normal intermediate position.

9. In a typewriting machine, the combination with a support for a set of types and a platen, one of which is shiftable to change the disposition of the types with respect to the platen, of a pair of oscillatory cam members connected with said shiftable part and having cam paths provided with dwells, a pair of key operated actuating devices each of which carries a roll which normally engages the dwell of one of said oscillatory members, each of said key operated members being adapted independently to actuate one of said oscillatory members in a direction opposite to that in which the other thereof is oscillated by the other of said key operated members, whereby the shiftable part may be moved in opposite directions from a normal intermediate position, and a roll carried by each of said key operated members adapted to engage one of said oscillatory members, said last named rolls coöperating with said oscillatory members to hold the shiftable part in a normal intermediate position.

10. In a typewriting machine, the combination with a support for a set of types and a platen, one of which is adapted to be shifted to change the disposition of the type with respect to the platen, an oscillatory cam member connected with the shiftable part and adapted when actuated to shift the same, an actuating device for said oscillatory member having means which normally engages the cam portion thereof.

11. In a typewriting machine, the combination with a support for a set of types

and a platen, one of which is adapted to be shifted with respect to the other to change the disposition of the types with respect to the platen, of oscillatory cam members connected with the shiftable part, the cam path of each of which is provided with a pair of dwells, one of which partly surrounds the axis of oscillation of said member, and the other of which is located at a position remote therefrom, and means for oscillating said member which normally engages the dwell of the cam path thereof which normally partly surrounds the axis of oscillation, said means being adapted to traverse said cam path from the last mentioned dwell to the other thereof whereby said member will be oscillated.

12. In a typewriting machine, the combination with type bars, each of which carries a plurality of types, and a shiftable platen, of an oscillatory cam member connected with the platen and adapted to shift the same, and means normally engaging said cam member at a point near the axis of oscillation for actuating the same.

13. In a typewriting machine, the combination with type bars, each of which carries a plurality of types, and a shiftable platen, of an oscillatory cam member connected with the platen and adapted to shift the same, and a key operated actuating device for said cam member provided with a pair of rolls, one of which engages the same to oscillate it, and the other of which engages the same to hold it in normal position.

14. In a typewriting machine, the combination with the type bars, each of which carries a plurality of types, and a shiftable platen, of an oscillatory cam member connected with the platen and adapted to shift the same, and a key operated actuating device for said cam member provided with a pair of rolls, one of which engages the cam member at a point near its axis of oscillation and is adapted to traverse the cam path thereof when actuated, the other of said rolls engaging said cam member at a point remote from its axis of oscillation and holding the same in normal position.

15. In a typewriting machine, in combination with the type bars, each of which is provided with a plurality of types, and a platen shiftable with respect to said types, of an oscillatory shift shaft connected with said platen, a cam member mounted upon said shaft and adapted to oscillate the same, and key operated means for actuating said cam member and for holding the same in normal position.

16. In a typewriting machine, in combination with the type bars, each of which is provided with a plurality of types, and a platen shiftable with respect to said types, of an oscillatory shift shaft provided with

an offset portion, a member provided with a cam path mounted upon said offset portion, and key operated means having a portion engaging said cam path at a point near the axis of oscillation of said shaft and adapted to traverse the same, whereby said member will oscillate said shaft and thereby shift the platen.

17. In a typewriting machine, the combination with the type bars, each of which is provided with a plurality of types, and a platen shiftable with respect to said types, of an oscillatory shift shaft connected with said platen, said shaft being provided with a yoke, a member provided with a cam path mounted upon said yoke, and key operated means having a portion engaging said cam path at a point near the axis of oscillation of said shaft and adapted, when actuated, to traverse the cam path, whereby said cam member will oscillate said shift shaft to thereby shift the platen.

18. In a typewriting machine, the combination with type bars, each of which is provided with a plurality of types, and a platen carriage shiftable with respect to said types, of an oscillatory shift shaft connected with the platen carriage and adapted to shift the same in opposite directions from a normal central position, said cam shaft being provided with a yoke, a plurality of members fixed upon said yoke each of which is provided with a cam path, and key actuated means adapted to traverse the cam path of said members to swing them in opposite directions, whereby said shift shaft is caused to move the platen carriage in opposite directions from its normal central position.

19. In a typewriter machine, the combination with the type bars, each of which is provided with a plurality of types, and a platen carriage shiftable with respect to said types, an oscillatory shift shaft suitably journaled in the framing of the machine and provided with an offset portion or yoke, a plurality of members provided with cam paths mounted upon said yoke each of which has a dwell partly surrounding the axis of oscillation of the shift shaft, a key operated member provided with a roll for actuating each of said cam members, the roll thereof normally engaging the dwell, each of said key operated members being adapted when actuated to oscillate said shift shaft in a direction opposite from that in which it is oscillated by the other thereof, whereby the platen carriage will be shifted in opposite directions from a normal intermediate position.

20. In a typewriting machine, the combination with a plurality of type bars, each of which is provided with a plurality of types, and a platen carriage shiftable in opposite directions from a normal central position to change the relation of the platen and said

types, an oscillatory shift shaft connected with the platen and adapted to shift the same in opposite directions from its normal central position, said shift shaft being provided with an offset portion or yoke, a plurality of members fixed upon said yoke, each of which is provided with a cam path, and a key actuated lever provided with a plurality of rolls for each of said cam members, corresponding rolls of said lever being adapted to engage their respective cam members at points near the axis of oscillation of said shift shaft, each of said rolls being adapted to traverse its cam path when the lever carrying the same is actuated, whereby the shift shaft may be oscillated in opposite directions, the other of said rolls being adapted to so engage their respective cam members that the platen carriage will be held in a normal central position.

21. In a typewriting machine, the combination with the type bars, each of which is provided with a plurality of types, and a shiftable platen, of a shift shaft provided with a yoke, arms extending from said shaft and connected with the platen, and means mounted upon said yoke adapted when actuated to oscillate the shift shaft in opposite directions, whereby the platen may be shifted in opposite directions from a normal intermediate position.

22. In a typewriting machine, the combination with type bars, each of which is provided with a plurality of types, and a shiftable platen carriage, of a shift shaft provided with a yoke, arms extending from said shaft, links extending between said arms and the platen carriage, and means mounted upon said yoke adapted when actuated to oscillate the shift shaft in opposite directions, whereby the platen will be shifted in opposite directions from a normal intermediate position.

23. In a typewriting machine, the combination with type bars, each of which is provided with a plurality of types, and a shiftable platen carriage, of a shift shaft provided with an off-set portion or yoke, arms fixed upon said shift shaft and extending therefrom, links connecting said arms with the platen carriage, means mounted upon said yoke adapted when actuated to oscillate the same, whereby the platen may be shifted, and means for compelling an equal movement of the opposite ends of the platen carriage when the same is shifted.

24. In a typewriting machine, the combination with the type bars, each of which is provided with a plurality of types, and a shiftable platen carriage, of an oscillatory shaft, suitably journaled in the frame of the machine, said shaft being provided with an off-set portion or yoke, arms fixed upon the opposite ends of said shaft and extending therefrom, a link connecting each of said

arms with the platen carriage, a pair of cam members mounted upon said yoke and adapted to be independently actuated to oscillate said shaft in opposite directions, whereby the platen carriage will be shifted in opposite directions from a normal central position, and an independent actuator for each of said cam members.

25. In a typewriting machine, the combination with the type bars, each of which carries a plurality of types, of a shiftable platen carriage, a shift shaft suitably journaled in the frame of the machine and having an off-set portion or yoke, an arm and link connection interposed between said shift shaft and the platen carriage, a pair of oscillatory cam members mounted upon said yoke and adapted to be actuated in opposite directions, and an actuator for each of said cam members, having means for traversing the cam path thereof, and also having means for engaging said members whereby they may be held in normal position.

26. In a typewriting machine, the combination with a plurality of type bars, each of which is provided with a plurality of types, of a vertically shiftable platen carriage, a rock shaft journaled in the framing of the machine and having an off-set portion or yoke, arms extending outwardly from said rock shaft, links interposed between said arms and the platen carriage, a pair of oscillatory members mounted upon said yoke, each of which is provided with a cam path having a plurality of dwells, the dwells of said cam paths which lie nearest said yoke partly surrounding the axis of rotation of said shaft, the other dwells of said cam paths being located at the opposite ends thereof, an independently operable actuating lever for each of said cam members, a roll carried by each of said levers adapted to traverse the cam path of one of said members, said rolls normally engaging the dwells of said cam paths which partly surround the axis of rotation of the shaft, said rolls when their levers are actuated being adapted to traverse their cam paths until they are carried into engagement with the other dwells thereof, whereby said members may be oscillated in opposite directions and the platen shifted in corresponding directions from a normal central position through its connection with said shaft, and a roll provided upon each of said levers which engages and holds one of said cam members against movement when the same is in normal position.

27. In a typewriting machine, the combination with the type bars, each of which has a plurality of printing characters, and a platen, of a platen shift frame adapted to move up and down from a normal intermediate position.

28. In a typewriting machine, the combination with the type bars, each of which has a plurality of printing characters, and a platen, of a platen shift frame adapted to move up and down from a normal intermediate position.

diate position, means for counterbalancing said platen frame, a rock shaft provided with an off-set portion or yoke, suitably journaled in the frame of the machine, arms 5 extending from said rock shaft, links connecting said arms with the platen frame, a pair of cam members fixed upon said yoke, and independent operated actuators for each of said cam members adapted to oscillate the 10 same in opposite directions, said actuators being adapted to coöperate to lock said cam members in normal position.

28. In a typewriting machine, the combination with the type bars, each of which is 15 provided with a plurality of printing characters, and a platen carriage, a shiftable rail upon which said platen carriage is mounted and upon which the same rides for letter spacing, a pair of independently operative 20 oscillatory cam members connected with said rail and adapted when actuated to shift the same to positions at either side of a normal central position, whereby the relation of the platen and types may be changed, and an 25 independent actuator for each of said cam members, adapted to oscillate the same in opposite directions.

29. In a typewriting machine, the combination with the type bars, each of which is 30 provided with a plurality of types, and a platen carriage, a shiftable rail upon which the platen carriage travels for letter spacing, means connected with said rail for compelling an equal movement of the opposite 35 ends thereof when the same is shifted, a rock shaft journaled in a fixed portion of the frame of the machine, arms extended from the opposite ends of said rock shaft, links connecting said arms with the opposite ends 40 of said rail, a pair of independently operable cam members mounted upon said rock shaft, the cam paths of each of said cam members being provided with a pair of dwells, one of the dwells of each of said 45 cam members partly surrounding the axis of rotation of said shaft, the other dwell of each of said cam members being located at a point remote from said axis, an actuating lever for each of said cam members, provided 50 with a roll which normally engages said first mentioned dwell, each of said rolls when its lever is operated being adapted to traverse its cam path until it reaches the other dwell of the cam member, whereby 55 said rail through its connection with said rock shaft will be shifted to change the position of the platen with respect to the types, and a second roll mounted upon each of said 60 actuating levers which engages the cam member which that lever is adapted to actuate when the cam member is in normal position, said latter rolls coöoperating to lock said cam members in their positions of rest.

30. In a typewriting machine, the combination with the type bars, each of which is

provided with a plurality of types, and a shiftable platen, a shift shaft provided with an off-set portion or yoke journaled in a fixed portion of the machine, connecting means interposed between said rock shaft 70 and the platen, whereby when said rock shaft will be oscillated in opposite directions and the platen shifted in corresponding directions from a normal central position, a pair of independently operable cam members 75 mounted upon said yoke, an actuator for each of said cam members provided with means which normally engages the cam member at a point near the axis of rotation of said shift shaft, whereby one of said actuators may remain inactive while the other thereof is operated to actuate its cam member.

31. In a typewriting machine, the combination with the type bars, each of which is 80 provided with a plurality of types, and a platen shiftable in respect to said types, a shift shaft having a yoke suitably journaled in a fixed portion of the frame of the machine, connecting means interposed between 85 said shift shaft and the platen, a pair of oscillatory cam members mounted upon said yoke, each of which has a portion of its cam path partly surrounding the axis of said shift shaft, an actuating lever for each of 90 said cam members which carries a roll adapted normally to engage the portion of the cam path partly at a point near the axis of the shift shaft, whereby one of said shift levers may be actuated while the other remains inactive.

32. In a typewriting machine, the combination with the type bars, each of which is provided with a plurality of types, and a platen adapted to be shifted to change its 100 position with respect to said type, of an oscillatory shift shaft journaled in a fixed portion of the frame of the machine, a connection between said shaft and the platen, whereby the latter may be shifted in opposite directions from a normal central position when the former is oscillated in opposite directions, said shift shaft being provided with an off-set portion or yoke, a pair 105 of cam members mounted upon said yoke and adapted to be swung in opposite directions to oscillate said shift shaft, said cam members being provided with cam slots, portions of which partly surround the axis of oscillation of said shift shaft, a pair of shift levers, each of which is provided with a roll which is adapted to traverse the cam slot of one of said cam members to oscillate the same, said rolls normally occupying the 110 portion of said cam slot partly surrounding the axis of oscillation of the shift shaft, whereby one of said levers may remain inactive while both of the cams on the shift shaft are being oscillated.

33. In a typewriting machine, the combi-

- nation with the type bars, each of which carries a plurality of types, and a platen carriage which is shiftable up or down in a vertical plane parallel with the plane of the faces of the types from a normal central position, of a shiftable rail upon which the platen carriage travels for letter spacing and means for shifting said rail, comprising a shift shaft journaled in a fixed portion 5 of the frame of the machine, a pair of arms extending from opposite ends of said shaft, links connecting said arms with said rail, said shaft having an off-set portion or yoke, a pair of oscillatory cam members mounted 10 upon said yoke, said cam members having cam paths, portions of which partly surround the axis of rotation of said shaft, a pivotally mounted actuating lever for each of said cam members, having a roll which traverses the cam path thereof and which normally engages that portion thereof which partly surrounds the axis of rotation of said shaft, the cam paths of said cam members being so disposed that when one is actuated, the shift shaft will be oscillated in a direction opposite to the direction in which it is oscillated when the other of said cam members is oscillated, whereby said rail may be shifted in opposite directions from a normal central position, and counterbalancing 15 means connected with the shift mechanism for returning the said rail to its normal position from either of its shifted positions. 20
34. In a typewriting machine, the combination with the type bars, each of which carries two or more types, and a platen adapted to be shifted with respect to said types, an oscillatory shift shaft connected with the platen, a pair of cam members 25 mounted upon said shift shaft, and a pivotally mounted actuating lever for each of said cam members provided with a roll which traverses the cam path thereof to oscillate it, and a roll which engages another portion thereof to hold it in normal position. 30
35. In a typewriting machine, the combination with the type bars, each of which carries a plurality of types, and a platen shiftable with respect to said types, shifting mechanism for the platen, comprising an oscillatory shift shaft journaled in the frame of the machine, an arm and link connection interposed between said shift shaft and the platen, said shift shaft being provided with an off-set portion or yoke, a pair of members having cam slots mounted upon said yoke, a key operated actuated lever for each of said members, having a roll which traverses the cam slots thereof to oscillate the same, and a roll which engages an exterior portion thereof for holding said cam member in normal position. 35
36. In a typewriting machine, the combination with the type bars, each of which carries a plurality of types, and a platen shift- 40 able with respect to said types, of an oscillatory shift shaft provided with a yoke suitably journaled in the frame of the machine, a pair of arms extending from the opposite ends of said shift shaft, a link connecting each of said arms with the platen at opposite ends thereof, a pair of oscillatory cam members mounted upon said yoke, each of which is provided with cam slots, having a pair of dwells, and one dwell of each of said cam slots partly surrounding the axis of oscillation of said shift shaft and the other dwell being located at a point remote therefrom, an independent pivotally mounted lever for each of said cam members, having a roll which engages said first mentioned dwell of the cam slot thereof, an adjustable support for the pivots of each of said levers, and keys for operating said levers, whereby said cam members may be oscillated. 45
37. In a typewriting machine, the combination with the type bars, each of which is provided with three types, and a vertically shiftable platen carriage adapted normally to be held in such position that the platen will receive imprints from the middle types of the type bars, said platen carriage being shiftable vertically to enable the platen to receive imprints from the lower or upper types of the type bars, a vertically shiftable rail 50 upon which said platen carriage is mounted and upon which it travels for letter spacing, spring counterbalancing means for returning the platen carriage to normal position from either position into which it has been shifted, and shifting mechanism for said rail, comprising an oscillatory shift shaft journaled in the frame of the machine, arms extending from the opposite ends of said shaft, links connecting said arms with the opposite ends of said rail, said shift shaft being provided with an off-set portion or yoke, a pair of oscillatory cam members mounted upon said shift shaft, said cam members being provided with cam slots, corresponding portions of which partly surround the axis of oscillation of said shift shaft, pivotally mounted actuating levers for said cam members, having rolls which are received in the cam slots thereof and which engage the walls of said slots at the points thereof near the axis of oscillation of said shift shaft, said cam slots being disposed in such relation that when one of said levers is swinging, causing the roll mounted thereon to traverse its cam slot, said cam member will be oscillated in a direction opposite to that in which the other cam member is swung when it is similarly actuated, a roll mounted upon each of said levers which engages an exterior portion of one of said cam members and holds the same in normal position, said latter roll co-operating to lock the platen carriage in its normal central position, a shift lever for swinging each of 55 60 65 70 75 80 85 90 95 100 105 110 115 120 125 130

said pivotally mounted levers, and a roll carried by each of the latter levers which engages a fourth portion of the shift lever.

38. In a typewriting machine, in combination, a stop for a movable part comprising a strip of sheet metal having one edge bent back upon itself, a suitable support to which said edge is secured, and a pad on the opposite exposed surface of said strip adapted 10 silently to arrest the movement of the movable part.

39. The combination in a typewriting machine, of means for arresting the movements of movable parts thereof comprising a thin 15 metallic strip bent back upon itself at its edges, and a suitable support to which the bent back edges of said strip are secured, thereby presenting a resilient surface to receive the impact of the movable member.

20 40. In a typewriting machine, in combination with movable parts thereof, of a stop for said movable parts comprising a thin metallic strip portions of which are bent back upon said strip, a covering of relatively 25 elastic material positioned upon the face of said strip and a support upon which the bent back edges of said strip are secured.

41. In a typewriting machine, the combination with a support for a set of types and 30 a platen, one of the parts being shiftable to change the disposition of the type with respect to the platen, of a pair of rotatably mounted cam members adapted when actuated to move the shiftable part in opposite 35 directions from a normal central position, an independent actuator for each of said cam members, and means connected with the shiftable part for compelling a movement of said shiftable part in a plane parallel to 40 that occupied by the other.

42. In a typewriting machine, the combination with a support for a set of types and a platen, one of which is shiftable to change the disposition of the type with respect to 45 the platen, of a pair of rotatably mounted cam members adapted when actuated to move the shiftable part in opposite directions from a normal central position, key operated means for actuating each of said 50 cam members and for holding them in a position of rest, whereby the shiftable part will be held in its normal central position, and swinging means connected with the shiftable part for compelling a movement 55 of the same in a plane parallel to that occupied by the faces of the types.

43. In a typewriting machine, the combination with a support for a set of types and a platen, one of which is shiftable to change 60 the disposition of the type with respect to the platen, of a pair of oscillatory members having cam paths adapted when actuated to move the shiftable part in opposite directions from a normal central position, a key

operated actuator for each of said members 65 having means for traversing the cam path thereof to thereby actuate the same, each of said key operated actuators having means which engages one of said oscillatory members and cooperates with the corresponding 70 means upon the other thereof to hold the shiftable part in its normal central position, and means pivotally connected with the frame of the machine and similarly connected with the shiftable part for compelling 75 a movement of the latter in the same plane in which it lies when at rest.

44. In a typewriting machine, the combination with a support for a set of types and a platen, one of which is shiftable to change 80 the disposition of the type with respect to the platen, of a pair of oscillatory members having cam paths connected with the platen, each of said members being adapted to move the shiftable part from a normal central position in a direction opposite to that in which it is moved by the other thereof, a key operated actuating device for each of said oscillatory members, provided with a part which traverses the cam path thereof thereby to actuate the same, each of said actuating devices being also provided with a part which limits the oscillatory movement of one of said cam members in one direction, and means connected with the shiftable part for 90 compelling such movement thereof as will carry it in a plane parallel to that occupied by the faces of the types when the latter are projected to the impression point.

45. In a typewriting machine, the combination with a support for a set of types and a platen, one of which is shiftable to change the disposition of the type with respect to the platen, of a pair of oscillatory cam members connected with the shiftable part, each 100 of which is adapted to shift the same from a normal central position in a direction opposite to that in which it is shifted by the other thereof, independently operated actuating devices for each of said oscillatory members 105 adapted to actuate the same and also adapted to hold the same in such position as will lock the shiftable part in its normal central position, and mechanism connected with the shiftable part for compelling a movement 110 thereof along a straight line when the same is shifted.

46. In a typewriting machine, the combination with a support for a set of types and a platen, one of which is adapted to be shifted to change the disposition of the type with respect to the platen, of an oscillatory cam member, connected with the shiftable part and adapted when actuated to shift the same, actuating devices for said oscillatory member, having means which normally engages the cam portion thereof at a position near the axis of oscillation, and means connected 115 120 125

with the shiftable part for compelling a movement thereof along a straight line when the same is shifted.

47. In a typewriting machine, the combination with the type bars, each of which carries a plurality of types and a platen frame carrying the platen, of a vertically shiftable rail upon which the platen frame is mounted and upon which it travels for letter spacing, 5 oscillatory cam members connected with said rail, the cam path of each of which is provided with a pair of dwells one of which partly surrounds the axis of oscillation of said member and the other of which is located at a position remote therefrom, means for oscillating one of said cam members which normally engages the dwell of the cam path thereof which normally lies in coincidence with the axis of oscillation, said 15 means being adapted to traverse said cam path from said last mentioned dwell to the other dwell thereof, whereby said member will be oscillated and said rail thereby shifted, and means connected with said rail for 20 compelling a movement thereof in a vertical plane when the same is shifted.

48. In a typewriting machine, the combination with the type bars, each of which is provided with a plurality of types and a 30 platen frame carrying the platen, of a vertically shiftable rail upon which the platen frame is mounted and upon which it travels for letter spacing, an oscillatory cam member connected with the platen and adapted 35 to shift the same, a key operated actuating device for said cam member provided with a pair of rolls, one of which engages the same to oscillate it and the other of which engages the same to hold it in normal position, and means connected with said rail for 40 compelling such movement thereof that the platen will be moved in a plane parallel to that occupied by the faces of the types.

49. In a typewriting machine, the combination with the type bars, each of which carries a plurality of types and a shiftable platen carriage carrying the platen, of an oscillatory cam member connected with the platen and adapted to shift the same, a key 50 operated actuating device for said cam member, and means for causing the platen carriage to move in a vertical plane when shifted, comprising a rock shaft and swinging arms connected therewith and with the platen carriage.

50. In a typewriting machine, the combination with the type bars, each of which carries a plurality of types and a platen frame shiftable in a direction transverse to its 55 length, of an oscillatory cam member connected with the platen and adapted to shift the same, a rock shaft journaled in a fixed portion of the machine, and means connected with said rock shaft and with said platen carriage for compelling a movement of the

latter in a direction parallel to the plane occupied by the faces of the types when the latter are projected to the printing point.

51. In a typewriting machine, the combination with the type bars, each of which carries a plurality of types and a platen shiftable in a direction transverse to its length for different case printing, of an oscillatory cam member connected with the platen and adapted to shift the same, a plurality of swinging members pivotally connected with the platen carriage and adapted to guide the same in its shifting movements, and means for changing the swinging radius of said members, whereby the platen carriage may move in a direction parallel to the faces of the types. 75

52. In a typewriting machine, the combination with the type bars, each of which carries a plurality of types and a shiftable 80 platen carriage, of a rail upon which the platen carriage is mounted and upon which it travels for letter spacing, an oscillatory cam member connected with said rail and adapted to shift the same, a pair of swinging members pivoted to said rail adapted to guide the same, pivotal supports for said swinging members located intermediate their ends and in which said members may slide during their swinging movements, and 85 means for causing said members to slide in said supports when said rail is moved to shift the platen carriage, whereby the swinging radius thereof will be so varied that said rail will be moved in a straight line. 90

53. In a typewriting machine, the combination with the type bars, each of which carries a plurality of types and a shiftable platen carriage, of a shiftable rail upon which the platen carriage is mounted and 100 upon which it rides during its letter spacing movements, an oscillatory cam member connected with said rail and adapted to shift the same, and means for effecting a vertical movement of said rail, whereby the platen will be carried in a plane parallel to the faces of the types when projected to impression, comprising a pair of swinging members one of which is connected to said rail at 105 each end thereof, a pivotal support for each of said members with which it is relatively slidably, a rock shaft, and a connection interposed between each of said members and said rock shaft adapted when said rail is moved to change the swinging radius of 110 said members, whereby said rail will be compelled to move in such plane as will move the platen in a plane parallel to that occupied by the faces of the types when they are projected to impression. 115

54. In a typewriting machine, the combination with the type bars, each of which carries a plurality of types and a shiftable platen carriage, of a shiftable rail upon 120 which the platen carriage is mounted and 125

upon which it rides for letter spacing, an oscillatory cam member connected with said rail and adapted to shift the same, a rock shaft journaled in a fixed portion of the 5 framing of the machine, and intermediate operative connections extending between either end of said rail and said rock shaft adapted to compel a movement of the former in a vertical plane when the same is 10 shifted.

55. In a typewriting machine, the combination with the type bars, each of which is provided with a plurality of types and a platen carriage shiftable vertically with respect to said types, of a vertically shiftable rail upon which the platen carriage is mounted and upon which it rides for letter spacing, an oscillatory shift shaft connected with said rail, said shaft being provided 15 with a yoke, a member provided with a cam path mounted upon said yoke, key operated means having a portion engaging the cam path of said member at a point near the axis of oscillation of said shaft and adapted 20 to traverse said cam path, whereby the cam member will oscillate said shift shaft to thereby shift said rail, and means for compelling a movement of the platen carriage in a vertical plane when said rail is shifted, 25 comprising a pair of arms one of which is connected to each end of said rail, a trunnioned support for each of said arms with which it has a sliding engagement, a rock shaft journaled in a fixed portion of the 30 framing of the machine, and a pair of arms extending from said rock shaft, each of 35 which is connected with one of said first mentioned arms.

56. In a typewriting machine, the combination with the type bars, each of which is provided with a plurality of types and a platen carriage shiftable vertically with respect to said types, of a vertically shiftable rail upon which the platen carriage is supported and upon which it rides for letter 40 spacing, an oscillatory shift shaft suitably journaled in a fixed portion of the framing 45

of the machine and provided with an off-set portion or yoke, a link depending from each end of said rail and pivotally connected therewith, the opposite ends of said links being connected with said shift shaft, a plurality of members provided with cam paths mounted upon said yoke, each of which has a dwell partly surrounding the axis of rotation of the shift shaft, a key operated member provided with a roll for actuating each of said cam members, the roll thereof normally engaging said dwell, each of said key operated members being adapted when 50 actuated to oscillate said shift shaft to a direction opposite from that in which it is oscillated by the other thereof, whereby the platen carriage will be shifted in opposite directions from a normal intermediate position, and means for compelling an equal movement of the opposite ends of said rail when the said links are actuated to move the same upward or downward from its normal central position, comprising a rock shaft 55 journaled in a fixed portion of the framing of the machine, a pair of arms one of which is extended from either end of said rock shaft, an arm pivotally connected with each of said first mentioned arms and similarly 60 connected with said rail at each end thereof, and a pivotal support for each of said latter arms in which it is adapted to slide.

57. In a typewriting machine, the combination with the side wall of the frame, a shift lever movable up and down substantially parallel to the surface thereof, laterally projecting members positioned above and below said lever, and means associated with the sides of said members adjacent the 65 shift lever for silently arresting the lever when contacting therewith.

In testimony whereof I affix my signature, in the presence of two witnesses.

NILS H. ANDERSON.
